UNITED STATES PATENT OFFICE.

WILLIAM H. WOOLUMS, OF CHICAGO, ILLINOIS.

MEMORANDUM-INDICATOR.

1,101,826.

Specification of Letters Patent. Patented June 30, 1914.

Application filed March 6, 1914. Serial No. 822,796.

To all whom it may concern:

Be it known that I, WILLIAM H. WOOLUMS, a citizen of the United States, residing at Chicago, in the county of Cook and State 5 of Illinois, have invented certain new and useful Improvements in Memorandum-Indicators, of which the following is a full, clear, concise, and exact description, reference being had to the accompanying drawings, forming a part of this application.

My invention relates to memorandum indicators for use in stores, households and similar places wherein commodities or supplies are used and where it is desirable to 15 keep a memorandum of supplies or commodities which are nearly exhausted for the purposes of making the proper purchases.

It will readily be seen that my invention has wide and varied application, but in order 20 to instruct those skilled in the art in the use of my invention, I shall describe it in its use as a household supply indicator.

In addition to the broad feature of my invention whereby the keeping of a memorandum is greatly simplified, I direct attention 25 to features of construction, to the end of simplicity and cheapness and to the end of securing a device of good appearance, and I have set forth these structural features 30 which lend to these more specific results in the more limited of the appended claims.

Broadly, my invention consists of a card or board which may conveniently be hung upon the wall, and which is provided with a 35 plurality of indicators which may either be lodged within pockets in said card or board or may be drawn out to be exposed, and, if desired, to expose the name of some particular article or commodity.

In order to secure a structure which will 40 be simple and inexpensive I construct a wall device which comprises one or more folded members, each of which is provided with a series of pairs of openings, and an indicator 45 slide is mounted in each pair of openings so that it may be moved inwardly or outwardly in order to either conceal or expose the name of a commodity printed thereon.

In the accompanying drawings Figure 1 50 is a front elevational view of the structure of my invention, parts being broken away to illustrate the interior construction; Fig. 2 is a cross-sectional view taken on the plane of the line 2—2 of Fig. 1; Fig. 3 is a developed 55 view of one of the folded members; Fig. 4 is a view of the indicators in the process of

manufacture; and Fig. 5 is a view of a modified form of my invention.

In the form of my invention illustrated herein, I prepare two flattened tubular members 7, 7 by folding together the sheet of paper, or similar material, illustrated in Fig. 3. This sheet of paper is folded longitudinally on the lines 7^a, 7^b, into the condition illustrated clearly in Fig. 2. It will be noted that the sheet 7 is provided with a series of openings 8 and a corresponding series of slots 9, the openings 8 occurring in a line in the face of one of the folds and the slots 9 occurring along the edge 7^a.

A series of indicator slides 10, 10, one for each pair of openings 8, 9, is provided, these indicator slides being primarily part of the integral strip 11. It will be seen that the stamping, illustrated in Fig. 4, is simply made and provides for the cutting of all the indicator slides for one row in a single operation, and the same may be said for the printing of these slides. The slides are then inserted in the openings 8, 9 down through 80 the opening 8 and out through the slit or slot 9 so that each of the slides will be mounted in a pair of openings, as illustrated in dotted lines in Fig. 3. As will then be seen from Fig. 2, the slides 10 may be moved into and 85 out of the tubular member 7 and it will be noted that each of the indicator slides 10 is provided with a head 12 which is too large to pass through the opening 8, and, thus, it is impossible to withdraw the indicator slide 90 10 entirely from the member 7. As will be noted in Fig. 2, two of these flattened tubular members 7 are provided, one for each side, and they are secured to a front piece 13 and a back piece 14, by means of stitching 95 15, 15 and, if desired, the front and back pieces may be provided with eyelets 16, by means of which the structure may be hung upon the wall.

As illustrated, each tubular member 7 is 100 secured at one side of the front piece 13 so that the indicator slides 10 may slide into and out of a position behind the front piece, as illustrated in Fig. 1, each of the slides being provided with the name of a commodity thereon, as illustrated, and the corresponding name is printed upon the front piece opposite the point where the corresponding slide is to be withdrawn.

It will be noted that in normal condition 110 the slides are all inserted and in this position they extend slightly beyond the side

of the front piece, so that they may be readily grasped by one's fingers and withdrawn into the outer position. In the inner position, the printing on the slide is concealed and in the outer position, it is exposed, as shown in Fig. 1. The slides are properly aligned in the interposition by the engagement of the heads 12 with the inner wall of the tubular member 7, as indicated by the 5 "cracker" indicator slide in Fig. 1, and, as before pointed out, the slides are limited in the extent to which they may be withdrawn by the engagement of the head 12 at the openings 8, as shown by the "eggs" indicator of Fig. 1. This arrangement leaves room for ornamental display upon the face 10 and for other useful articles, such as a calendar, for instance.

In Fig. 5, I have illustrated a view corresponding to Fig. 2 except that in Fig. 5 20 there is illustrated a form of my invention wherein the various necessary walls are formed by a certain folding of a single sheet of material.

25 I claim:

1. In a memorandum indicator, a folded member comprising a fold having a series of pairs of openings therein, and a series of indicator members, each mounted in a pair of 30 said openings.

2. In a memorandum indicator, a folded member comprising a fold having a series of pairs of openings therein, and a series of indicator members, each mounted in a pair of 35 said openings, and having a head to prevent withdrawal thereof from said openings.

3. In a memorandum indicator, a flattened tubular member having a series of openings in a face wall thereof and a corresponding series of openings in the side thereof, and an indicator mounted to slide in each pair of openings to move a portion 40 thereof into and out of said tubular member.

4. In a memorandum indicator, a flattened tubular member having a series of 45

openings in a face wall thereof and a corresponding series of openings in the side thereof, and an indicator mounted to slide in each pair of openings to move a portion thereof into and out of said tubular member, and a head on each of said indicators to limit the movement thereof.

5. In a memorandum indicator, a flattened tubular member having a series of openings in a face wall thereof, and a corresponding series of openings in the side thereof, and an indicator mounted to slide in each pair of openings to move a portion thereof into and out of said tubular member, and a head on each of said indicators inside 50 55 said tubular member to limit the movement thereof.

6. In a memorandum indicator, a flattened tubular member having a series of openings in a face wall thereof and a corresponding series of openings in the side thereof, and an indicator mounted to slide in each pair of openings to move a portion thereof into and out of said tubular member, 60 said portion having the name of a commodity 65 thereon.

7. In a memorandum indicator, a pair of flattened tubular members each having a series of openings in a face wall thereof and a corresponding series of openings in the outer side thereof, an indicator mounted to slide in each pair of openings to move a portion thereof into and out of said tubular member, and a face member and a back member between which said tubular members are 70 secured, said portions having the names of commodities thereon and said face member having corresponding notations.

In witness whereof, I hereunto subscribe my name this 2nd day of March, A. D. 1914. 75 80 85

WILLIAM H. WOOLUMS.
